UNITED STATES PATENT OFFICE.

SYLVESTER B. HUSCH AND GEORGE S. HUSCH, OF NEW YORK, N. Y.

TOOTH-BRUSH.

1,080,634.

Specification of Letters Patent.

Patented Dec. 9, 1913.

Application filed April 5, 1913. Serial No. 759,016.

To all whom it may concern:

Be it known that we, SYLVESTER B. HUSCH and GEORGE S. HUSCH, both citizens of the United States, residing at New York city, county and State of New York, have jointly 5 invented a new and Improved Tooth-Brush, of which the following is a specification.

This invention relates to a tooth brush of novel construction which comprises essentially 10 a tubular magazine and a plurality of bristle bundles contained therein and adapted to be successively projected from the nozzle thereof. In this way a fresh bundle may be used at each operation, so that cleanliness 15 is insured and sanitary requirements are complied with.

The invention also comprises various other features of construction, all as more fully pointed out in the specification and 20 appended claims.

In the accompanying drawing: Figure 1 is a side view of a tooth brush embodying our invention; Fig. 2 a plan; Fig. 3 an enlarged longitudinal section partly in side 25 view; Fig. 4 a similar section through a further modification.

Referring more particularly to Figs. 1-3, the tooth brush comprises essentially a rigid tubular casing or magazine 10 having a 30 curved nozzle 11. To the forward end of casing 10, there is pivoted in bearings 12, a curved jaw 13, normally depressed by a spring 14 and extending with its bent forward end in front of the upper shortened 35 end of nozzle 11. Within casing 10, there is contained a plurality of short bristle bundles 15, said bundles being inclosed by a common breakable wrapper 16 to constitute a core. The magazine is charged with this core from 40 the rear, it being here provided with a screw cover 17.

In use, the core is pulled forward until the end of the foremost bundle 15 protrudes from the nozzle, such bundle being held in 45 position by the spring action of jaw 13.

After the brush has been used, the jaw is opened, and the core pulled out to expose a

fresh bristle bundle, while the old bundle together with its wrapper is torn off and thrown away. In this way, a clean bundle 50 is available for each operation, so that cleanliness is insured.

In Fig. 4, the magazine 25 has a tapering nozzle 26 and contains a plurality of bristle bundles 27. These bundles are successively 55 advanced by means of a screw plunger 28 that engages the rear threaded end of the magazine and carries a knob 29, by means of which the plunger may be turned.

It will be seen that by the construction 60 described, the magazine may be recharged from time to time with a new lot of bristle bundles, so that the magazine will constitute a permanent addition to the toilet, which may be used with an unlimited number of 65 said bundles.

We claim:

1. A tooth brush comprising a rigid tubular magazine having a nozzle and a plurality of inclosed bristle bundles, said bundles 70 being adapted to be successively projected from said nozzle.

2. A tooth brush comprising a tubular casing having a curved nozzle, and a spring-influenced jaw, pivoted to the casing and cooperating with said nozzle, a plurality of bristle bundles inclosed within the casing, and a breakable wrapper encompassing the 75 bristle bundles.

3. A tooth brush comprising a tubular 80 casing having a curved nozzle, provided with an upper shortened section, a curved spring-influenced jaw pivoted to the casing and having a bent forward end extending in front of the shortened nozzle section, a plurality of bristle bundles inclosed within the 85 casing, and a breakable wrapper encompassing the bristle bundles.

SYLVESTER B. HUSCH.
